UNITED STATES PATENT OFFICE.

RICHARD EWELL MOONEY, JR., OF GREENEVILLE, TENNESSEE, ASSIGNOR TO THE AMERICAN CALENDAR CO., INC., OF GREENEVILLE, TENNESSEE.

DESIGN FOR AN ADVERTISING SIGN OR THE LIKE.

Application filed May 18, 1929. Serial No. 31,283. Term of patent 7 years.

To all whom it may concern: Be it known that I, RICHARD EWELL MOONEY, Jr., a citizen of the United States, residing at Greeneville, in the county of Greene and State of Tennessee, have invented a new, original, and ornamental Design for Advertising Signs or the like, of which the following is a specification, reference being had to the accompanying drawing, forming part thereof. The figure is a face view of an advertising sign or the like, showing my new design. I claim: The ornamental design for an advertising sign or the like, as shown.
